WINDOW SASH FASTENER

Filed June 9, 1930

William N. Cropper
Inventor

By *W. L. Symons*
Attorney

UNITED STATES PATENT OFFICE

WILLIAM N. CROPPER, OF LEXINGTON, KENTUCKY

WINDOW SASH FASTENER

Application filed June 9, 1930. Serial No. 460,027.

My invention relates to improvements in window sash fasteners and more particularly to a device for locking the sashes of a window in open or ventilating position.

5 An important object of my invention is the provision of a device of this character which will lock the sashes of a window in ventilating position and which cannot be manipulated from the exterior of the window.

10 Another object of my invention is to provide a device of the above mentioned character which is simple of construction and operation, inexpensive to manufacture and install, and strong and durable in use.

15 Other objects and advantages of my invention will be apparent during the course of the following description.

In the accompanying drawings, which form a part of this specification and wherein like characters of reference denote like or corresponding parts throughout the same,

Figure 1 is a perspective view showing my improved sash fastener applied to a window.

Figure 2 is a front elevation of my invention in its operative position,

Figure 3 is a similar view showing my invention in its inoperative position,

Figure 4 is a side elevation of my improved sash fastener, portions of the window sashes being shown in section,

Figure 5 is a vertical sectional view through the sash fastener,

Figure 6 is a perspective view of the keeper, and,

Figure 7 is a similar view of the locking bolt.

In the drawings, wherein for the purpose of illustration is shown a preferred embodiment of my invention, the numeral 10 designates the frame of a window having an upper sash 11 and a lower sash 12.

The side rail of the lower sash 12 is provided with an opening 13 spaced a substantial distance from the top of the sash and extending completely through the sash. A bolt 14 having an enlarged head is arranged in the opening 13 and when the head of the bolt abuts against the inner face of the sash rail, its end projects a substantial distance beyond the outer face of the sash rail. When the

upper sash 11 is lowered it will rest upon the projecting outer end of the bolt 14, as shown in Figures 4 and 5, the bolt acting as a stop for the upper sash.

In order to prevent the removal of the bolt 14, as by pushing it through the opening 13 from the outside, and to serve as a lock for the lower sash, I provide a combination guard plate and catch 15 which is spaced from the inner face of the lower sash rail by a collar or spacer 16. A bolt or screw 17 extends through an opening in the upper end of the guard plate 15 and through the collar 16 into the sash rail at a point above the opening 13, and is firmly secured to the sash rail by means of suitable screw-threads or the like.

The lower end of the guard plate 15 is provided with an opening 18 having a keyway or notch on its upper side, the opening 18 being adapted to correspond, when the plate 15 is in its lower position, with an opening or bore 19 in the sash rail, which does not extend entirely through the sash rail. A lock bolt 20 is adapted to extend through the opening 18 and into the opening 19. The bolt 20 is provided with an enlarged flattened head 21 and a peg or key 22 spaced from the head and extending radially from the bolt.

When the bolt 14 is in place and the plate 15 is pivoted about the screw 17 into its lowermost position, the locking bolt 20 is inserted in the openings 18 and 19 and the key 22 passes through the keyway in the plate. The locking bolt 20 is then rotated to move the key away from the keyway and the bolt 14 is locked in position against removal, by the guard plate. The bolt 14 cannot be pushed through the opening 13 to allow the upper sash to pass until the locking bolt 20 is rotated and withdrawn, and the guard plate 15 pivoted into the position shown in Figure 3.

In order to lock the lower sash in a partially raised position, I provide the edge of the guard plate nearest the window frame with a lateral extension 23 having a rounded lower end. A keeper 24 is formed with an open side, the other side of the keeper being provided with openings to receive securing screws which secure the keeper to the inside edge of the window frame adjacent the

groove which receives the lower sash. When the guard plate 15 is swung into its lower position the lateral extension 23 enters the keeper 24 and prevents movement of the lower sash in either direction.

The keeper 24 is so arranged that when the plate 15 engages the keeper, the lower window sash will be raised sufficiently to allow ventilation. The upper sash may then be

10 lowered to rest upon the bolt 14 and the window will then ventilate above and below the sashes. While either sash may be opened, and the other remain closed, it is preferred to lock both sashes in partially open position.

15 It will be seen that the guard plate 15 acts to prevent removal of the bolt 14 as well as engaging the keeper 24 to lock the lower sash.

20 While I have shown and described the preferred embodiment of my invention it is to be understood that various changes in the size, shape, and arrangement of parts may be resorted to without departing from the spirit of my invention or the scope of the sub-
25 joined claims.

Having thus described my invention, what I claim and desire to protect by Letters Patent is:

30 1. In a ventilating device for a window having upper and lower sliding sashes, the lower sash having an opening extending therethrough at a point spaced from its upper end, a bolt arranged in said opening and extending beyond the outer face of the sash
35 for a substantial distance, a guard plate pivoted to the inner face of the lower sash adjacent the bolt and adapted to be swung over the inner end of the bolt to prevent its removal, and means to secure the pivoted guard plate in its operative position.

40 2. In a ventilating device for a window having a frame and upper and lower sliding sashes, a stop member extending through the lower sash at a point spaced from the upper end thereof and projecting outwardly beyond the sash for a substantial distance, a guard plate secured to the lower sash adjacent the stop member and adapted to be moved to cover the inner end of the stop member, a keeper on the window frame and a lateral extension on the guard plate adapted to enter said keeper.

45 3. In a ventilating device for a window having a frame and upper and lower sliding sashes, the lower sash having an opening therethrough spaced from the upper end thereof, a bolt arranged in said opening and projecting beyond the sash for a substantial distance, a guard plate pivoted to the lower sash adjacent the opening therein and adapted to cover the inner end of the bolt, a keeper secured to the window frame, a member on the guard plate adapted to engage said keeper, and means to secure said guard plate in
55 operative position.

4. In a ventilating device for a window having a frame and upper and lower sliding sashes, the lower sash having an opening therethrough spaced from the upper end thereof, a bolt having an enlarged head, said bolt being arranged in said opening and projecting outwardly beyond the sash for a substantial distance, a guard plate spaced from said sash and pivoted thereto at a point adjacent the opening therein, said plate being adapted to cover the head of the bolt when in its operative position, a keeper secured to the window frame, and a lateral extension on the guard plate adapted to engage said keeper when the plate is in its operative position.

5. In a ventilating device for a window having upper and lower sashes, the lower sash having an opening therethrough, a bolt having a head at one end, said bolt being removably arranged in said opening in the sash and projecting a substantial distance therebeyond, a guard plate pivoted to said lower sash adjacent the opening therein and adapted to cover the head of the bolt when arranged in its operative position, said plate having an opening therein provided with a notch, said opening in the plate registering with an opening in the sash in the operative position of the plate, and a locking bolt adapted to be received in the registering openings in the plate and sash and having a key adapted to fit into the notch in the plate opening.

6. In a ventilating device for a window having a frame and upper and lower sashes, the lower sash having an opening therethrough, a bolt having a head at one end, said bolt being removably arranged in said opening in the sash and projecting a substantial distance therebeyond, a guard plate pivoted to said lower sash adjacent the opening there-
100 in and adapted to cover the head of the bolt when arranged in its operative position, said plate having an opening therein provided with a notch, said opening in the plate registering with an opening in the sash in the operative position of the plate, a locking bolt adapted to be received in the registering openings in the plate and sash and having a key adapted to fit into the notch in the plate opening, a keeper secured to the window frame, and a lateral extension on said guard plate adapted to engage said keeper in the
110 operative position of the guard plate.

7. In a ventilating device for the sashes of a window, a removable stop member extending through one of the sashes and projecting therebeyond to provide a stop for the other sash, a movable guard plate adapted to be moved over a portion of the stop member to prevent its removal, and means to lock the guard plate in operative position.

8. In a ventilating device for a window having a frame and sliding sashes, a stop member extending through one of the sashes and projecting therebeyond to provide a stop

for the other sash, a movable guard plate adapted to be moved over a portion of the stop member to prevent its removal, and means on said guard member to engage the 5 window frame.

In testimony whereof I affix my signature.

WILLIAM N. CROPPER.
